UNITED STATES PATENT OFFICE.

NORMAN BLEULER, OF SOUTH BEND, INDIANA.

EGG-BEATER.

1,101,781.

Specification of Letters Patent. Patented June 30, 1914.

Application filed May 14, 1913. Serial No. 767,535.

To all whom it may concern:

Be it known that I, NORMAN BLEULER, a citizen of the United States, and a resident of South Bend, in the county of St. Joseph and State of Indiana, have invented a new and Improved Egg-Beater, of which the following is a full, clear, and exact description.

This invention relates to culinary apparatus and has particular reference to beaters and stirrers generally.

Among the objects of this invention is to produce a rotary beater having several related parts which may be readily disconnected for sanitary and cleansing purposes, the device consisting of the fewest possible number of separate parts and adapted to occupy a minimum amount of space proportional to its agitating or beating efficiency.

The foregoing and other objects of this invention will hereinafter be more fully described and claimed and illustrated in the drawings forming a part of this specification in which like characters of reference indicate corresponding parts in all the views, and in which—

Figure 1 is a front elevation of the device made in accordance with a preferred embodiment of this invention, a part of said figure being broken away; Fig. 2 is a view at right angles to Fig. 1, also partly broken away; Fig. 3 is a transverse sectional detail on the line 3—3 of Fig. 2; and Fig. 4 is a detail on the line 4—4 of Fig. 1.

The several parts of the device may be made of any suitable materials and the relative sizes and proportions of the same may be varied to a considerable extent without departing from the spirit of the invention hereinafter more fully set forth and specifically claimed.

At 10 I show a frame or bracket constituting the main support for the several parts of the device. The operating parts comprise a master gear 11 having a hub 12 through which the gear is pivoted by means of a pivot bolt 13 to the intermediate portion 14 of the frame. The frame is provided with an upwardly projecting handle 15 of any suitable or well known form whereby the device is held in one hand while the master gear is turned by a handle 16 by the other hand.

The beater or agitator parts proper comprise a loop 17 of any suitable form shown,

however, as substantially circular and having an opening 17' at its bottom. The upper portion of the loop is rigidly connected to arms 18 secured at the upper ends to a pinion 19 arranged within a yoke 20 at the lower portion of said frame. Said yoke includes a fork 21 embracing the collar 19' just beneath the pinion 19. Said frame also includes a pair of laterally projecting parallel members 22 and 23 at the lower and upper ends of the portion 14 aforesaid. Said portion 22 of the frame is arranged in close spaced relation to the fork 21 and by this means the pinion 19 is maintained in place and in mesh with the gear 11. A brace 18' connects the lower portions of the arms 18.

The other principal part of the beater or agitator mechanism consists of a central shaft 24 to which are secured a series of transverse fingers 25 and 25', the latter of which at the upper and lower ends of the series are slightly curved and said curved fingers and the ends of the other fingers sweep around closely within the path of the loop 17 and in the opposite direction from the rotation of said loop. The shaft 24 extends upwardly through said brace, yoke, pinion 19 and frame members 22 and 23, and has connected to its upper end in any suitable easily detachable way a second pinion 26 also in mesh with the master gear 11 but which being on the opposite side of the pivot 13 from the pinion 19 is driven in the opposite direction therefrom. Each of the pinions, therefore, serves in the nature of an anti-friction roller for the other pinion, and by this construction the likelihood of the slipping of the master gear from the driven pinions, due to looseness of the bearings, will be practically eliminated.

The purpose of the open space 17' at the bottom of the loop is to avoid a joint or bearing contact between the two parts of the agitator in this part of the device. It also provides a means for the easy separation of the two movable parts of the agitator, for, by removing the pin 27 which secures the upper end of the shaft 24 to the pinion 26, the said shaft with the fingers connected thereto may be slipped bodily outward through said opening without obstruction. Under ordinary conditions, however, the pinion 19 and collar 19' will be retained in normal position within said yoke. The lower end or point 28 of the shaft 24

constitutes the main bearing or supporting point for the device while in use. Since the lower end of the shaft 24 rests upon the bottom of the dish and sustains the thrust upon the handle 15, I provide a lug 15' extending laterally from the handle and in coöperation with the upper end of the shaft 24 constitutes a step bearing.

It is to be noted that the movable parts 10 of this beater are practically open and there is no possibility of material to become lodged tending to make the device unsanitary. Whether or not the parts are separated for thorough cleansing, the material 15 being treated may readily be washed or rinsed from the device.

Having thus described my invention, I claim as new and desire to secure by Letters Patent:—

20 In an egg beater, the combination of a supporting member including a vertical central portion, laterally extending bearing members at the upper and lower ends thereof, and a yoke extending downwardly from 25 and extending thence laterally parallel to the lower frame bearing member, a vertical

sleeve extending within said yoke, an agitator member comprising an open bottomed loop secured to the lower end of said sleeve, a shaft extending vertically through said shaft, sleeve, yoke and frame bearing members, a series of beater fingers secured to said shaft within said loop, the shaft and said fingers being movable downwardly through the opening in the bottom of the 35 loop, a master gear pivoted centrally of said intermediate frame member, and a pair of pinions meshing with and driven in opposite directions by said master gear, one of said pinions being connected to the upper 40 end of the sleeve within the yoke and the other being connected to the upper end of the shaft above the uppermost frame bearing member.

In testimony whereof I have signed my 45 name to this specification in the presence of two subscribing witnesses.

NORMAN BLEULER.
